VIBRATING UNIT

Frank Emery Hutchison, Lake Bluff, Ill.

Application January 31, 1939, Serial No. 253,769

13 Claims. (Cl. 210—152)

This invention relates to vibrating units and more particularly to vibrating screen units for use in reclaiming or reconditioning mud used during the process of drilling oil wells.

The mud used in the process of drilling oil wells is of a certain consistency and is flowed or pumped to cause it to continuously circulate in the hole being drilled for the purpose of carrying away the rock cuttings from the drill and for sealing the rock fissures through which the hole passes. In its circulation through the well, the mud becomes contaminated with one or more of several impurities including sand and shale mixed with the mud during drilling, which particles render the mud ineffective for the purpose intended and necessitate the removal of such particles to condition the mud for further use.

An object of the invention is to provide a more efficient and practical vibrating unit.

In accordance with the object of the invention one embodiment thereof comprises a vibrating unit positioned in the path of a substance to be screened, the unit comprising a housing with channel members adjacent the entrance end thereof for receiving the outer edges of a resilient member, serving as a dam for the substance and as a support for the vibrating frame including a channel portion to receive the inner edges of the resilient member. The vibrating frame supports the screen cloth in the path of travel of the substance and at an angle with respect thereto so that vibration of the screen cloth and frame will readily free undesired particles from the substance.

Other objects and advantages will be apparent from the following detailed description taken in conjunction with the accompanying drawings, wherein

Fig. 1 is a side elevational view of the vibrating unit, portions thereof being broken away;

Fig. 2 is a vertical sectional view through pits in the path of a flowing substance, illustrating one manner in which the vibrating unit may be employed;

Fig. 3 is a front elevational view of the vibrating unit, portions thereof being broken away;

Fig. 4 is a fragmentary sectional view taken along the line 4—4 of Fig. 3, and

Fig. 5 is a fragmentary sectional view taken along the line 5—5 of Fig. 3.

Referring now to the drawings, particularly Figs. 1 and 3, the vibrating unit comprises a housing 10, U-shaped in general contour and formed of suitable material, such as sheet metal. Both ends of the housing are open and the end

5 housing the vibrating frame and screen will hereinafter be referred to as the entrance end while the other will be referred to as the exit end. The entrance end of the housing is tapered, as shown in Fig. 1, and secured to the bottom and side walls of the said entrance end are spaced sets of angle members 11 and 12. As shown in Figs. 1, 3 and 4, the sets of angle members 11 and 12 extend parallel with the adjacent edge 10 of the housing forming a recess therebetween in which channel retaining members 14 are disposed and secured to the housing. The channel members 14 are, as well as the angle members 11 and 12, formed of individual members for the bottom and side walls of the housing, yet if so desired they may each be formed in single units. As shown in Fig. 3 angle members 11 and 12 terminate at the upper edge of the housing while the channel member 14 extends there above where there is secured a cross channel member 15.

20 A resilient supporting member 16 of the cross-sectional contour shown in Figs. 1 and 4 is disposed in the channel retaining member 14 and may either be formed of a single U-shaped piece 25 or of individual straight pieces. The material of which the resilient supporting member is formed may be rubber or other materials suitable for such purpose such as Duprene.

25 A vibrating frame indicated generally at 20 is supported entirely by the resilient supporting member 16 and comprises a square shaped channel member 21 positioned to receive the inner edges of the member 16 in the bottom and side 30 portions thereof. The top portion of the channel member 21 has its side wall projections extending downwardly as shown in Figs. 1 and 3. The frame 20 further consists of a plurality of 35 triangular sections, three of which are employed 40 in the present embodiment, these sections being spaced as shown in Fig. 3 and consisting of vertical channel portions 23 secured at their ends to the top and bottom portions of the channel member 21, lateral channel portions 24 with their 45 inner ends fixed to the upper ends of their respective vertical portions, and transversely extending portions 25 extending between the spaced ends of their respective vertical and lateral portions (Fig. 1) where they are secured in place.

50 To further connect the frame 20 with the resilient supporting member 16 channel members 28 are fixed to the upper corners of the frame, as shown in Fig. 3, and extend over the upper ends of the supporting member. Integral projections 29 of the channel members 28 project

into the channel portions of the side members 14.

A screen element 30, which may be any suitable porous or apertured element, such as woven wire cloth as shown in the present embodiment of the invention is secured to the frame 20 to completely cover the opening therein. The upper and lower edges of the screen element 30 have hook members 31 fixed thereto. An angle member 32 fixed to the bottom portion of the member 21 of the frame 20 provides an edge, which extends substantially the full width of the frame around which the lower hook member 31 may be positioned, as shown in Fig. 1. The upper hook member 31 rests upon the outer edge of a tensioning or retaining clamp 35, substantially U-shaped in cross-section, and having an inner edge removably positioned to abut the inner lower edge of the top portion of the channel member 21. To guide the clamp into the position shown in Fig. 1, an angle member 37 is fixed to the same portion of the channel member 21 and has its lower portion extending transversely therefrom. The triangular sections of the frame 20, mainly the vertical portions 23 thereof provide an interrupted wall for further assuring the positioning of the clamp 35. Suitable means may be provided to move the clamp about its inner edge as a fulcrum to move the outer edge thereof upwardly to draw the screen element taut across the opening of the frame. In the present embodiment bolts 38 are employed to accomplish this purpose, the bolts being suitably spaced and extending through apertures in the clamp 35 and channel member 21. It is therefore, possible to remove the screen element 30 by loosening the bolts 38 to allow sufficient movement of the clamp 35 to free the hook members 31.

It is important that the substance acted upon by the unit, which in the present embodiment is a fluid termed "mud" employed in drilling oil wells, be prevented from continuing its flow other than through the screen element 30. The formation of the hook members 31, the angle member 32 and the clamp 35 seal the upper and lower edges of the screen element. To seal the side edges of the screen element 30 sealing strips or members 40 are employed. The sealing strips 40 may be formed of suitable material, for example sponge rubber, and may be secured in place as desired. As an example these strips may be glued or vulcanized to the side edges of the screen element or may be disposed in suitable recesses of the frame. These sealing strips fill the space between the overlapping side edges of the screen element and the member 21 of the frame and may be of greater thickness than this space so that it may be compressed when the screen element is drawn taut.

A vibrating element, indicated generally at 45 when actuated, through any suitable power means, such as a motor 46, causes vibration of the frame 20 in its resilient support 16 to cause vibration of the screen element 30.

The vibrating element 45 comprises a tubular casing 47 closed at its ends by caps 48 and 49 and supporting bearings 50 within its ends. An out-of-balance shaft 53 has reduced axially aligned ends 54 and 55 supported by the bearings 50 and positioned eccentrically with respect to the main portion of the shaft.

The casing 47 is supported at spaced positions by resilient supports 58 in the form of annular elements of suitable material such as soft rubber. 75

As illustrated in Fig. 3 pairs of the support 58 are disposed concentric with the casing and housed in brackets 60 mounted upon the frame 20 at the triangular sections thereof.

5 To connect the shaft 53 to the motor 46, the end 55 of the shaft is extended through an aperture in the cap 49 and provided with a pulley 62 which is connected to a pulley 63 of the motor through belts 64.

10 The motor 46 is mounted upon a stationary platform supported by the housing 10. As illustrated in Figs. 1 and 3 channel members 68 have their forward ends mounted upon the channel member 15, the other ends thereof being mounted upon an angle member 69. Suitable means, such as transverse members 70, extending between the angle members and the side channel members 14 support the rear portion of the platform. A plate 71 mounted upon the channel members 68 completes the platform for the motor.

Upon considering the operation of the unit, attention is first directed to Fig. 2 which illustrates one use therefor; namely, the reconditioning of the fluid or mud used in drilling oil wells. Here a trough 74 is shown receiving the fluid from the hole being drilled. The trough directs the fluid to a pit 75 of sufficient size to receive a large quantity of the fluid and the undesired substances therein. Another pit 76 is positioned to receive the reconditioned fluid whereas the unit is mounted between the pits in the path of the fluid. An overflow 77 for the pit 76 directs the reconditioned fluid back to the hole being drilled for further use. The unit is suitably embedded between the pits so that the fluid, that is the desired portion thereof, cannot flow other than through the unit. Angle members 80 fixed to the housing are secured to cross beams 81, the latter extending across the pits and assist in supporting the unit and holding it against displacement.

With this illustration in mind, attention is directed to the operation of the unit. Actuation 45 of the motor 46, by a suitable power means not shown, causes rotation of the shaft 53. Rotation of the shaft creates a vibrating force due to the eccentric positioning of the weighted or heavier portion of the shaft with respect to its axis of rotation. This vibrating force is transmitted to the screen element through the bearings 50, the casing 47, the resilient supports 58, the brackets 60 and the frame 20.

The resilient supports 58, in being interposed between the vibrating means, or vibrating motion creating element (the shaft 53) and the frame 20, do not decrease the efficiency of the vibrating means but serve to cushion the vibrating motion and are especially effective in preventing damage to the parts in the vibrating chain when undue jarring occurs, for example at the beginning of the operation of the unit. Even during the regular operation of the unit the resilient supports 58 remove that strain on the parts in the vibrating chain and the possible damage to such parts should they be directly connected metal throughout.

Vibration of the screen element is made possible through its resilient supporting member 16, which member also serves as a seal between the housing 10 and the frame 20, and further serves as a dam against the fluid, permitting its passage only through the screen element.

Therefore, in positioning the unit in the path of the fluid and so that it will extend a sufficient

distance thereabove, further passage of the fluid, after entering the pit 75, must be through the screen element and the housing. By viewing Figs. 1 and 2 it will be observed that the fluid in its natural flow will move to the screen element where the apertures in the element will permit passage of the desired portion of the fluid therethrough but will prevent passage of the undesired portions. The undesired portions, which, as a rule, are solids heavier in proportion to the desired portion of the fluid, move toward the unit against gravity, resulting in movement thereof at a much slower velocity than would occur should such portions be dropped by gravity on a horizontally positioned screen. The positioning of the screen element vertically, in the path of the fluid and at an angle away from the point of contact of such portion, instead of horizontally, relieves the screen of the full weight of the fluid, the added weight increased by gravity in dropping the fluid on the screen, the added weight of the undesired portions remaining thereon until they reach the end of the screen and the result of losing some of the undesired portions through the screen due to the length of time such portions remain on the screen.

Therefore, instead of the force of gravity tending to cause the solids, or undesired portions of the fluid, to pass through the screen element or block the apertures in the screen, it acts to move such portions free of the screen thus aiding the vibrating means in freeing the screen of them and making possible an undisturbed full capacity passage of the desired fluid portion through the screen. When the solids strike the screen element they are pushed away therefrom by the vibrating motion of the screen. The force of gravity acts to move the solids downwardly. As the solids move downwardly less force is present in the fluid to move the solids toward the screen, thus increasing the time interval for the force of gravity to be effective. The angular position of the screen also assists in increasing this time interval as the farther the solids drop the farther they must travel to reach the screen.

Therefore, due to the fact that the undesired portions of the fluid may be readily moved free of the screen, screens of finer mesh then could effectively be used on horizontal screen units, without the undesired portions of the fluid closing the apertures, may be used if so desired. Furthermore, due to the same fact, screens of coarser mesh or larger apertures may be used, allowing a faster flow of the fluid with an equal or more efficient removal of the undesired particles then is possible with finer mesh screens of the horizontal type screen.

The embodiment of the invention herein disclosed is illustrative only and may be widely modified and departed from in many ways without departing from the spirit and scope of the invention as pointed out in and limited only by the appended claims.

What is claimed is:

1. A vibrating unit comprising a channel, for a fluid, formed to direct the fluid in a definite path, an apertured member, a resilient element to support the member in the channel across the path of the fluid and constantly serve as a dam against the passage of the fluid other than through the member, and means to cause vibration of the member to force undesired portions in the fluid from the member and allow portions of the fluid to pass therethrough.

2. A vibrating unit comprising a channel, for

a fluid, formed to direct the fluid in a definite path, a resilient supporting element disposed in the channel, an apertured member disposed across the path of the fluid, a frame carrying the apertured member and supported by the resilient element, means disposed between the frame and the member to form a fluid seal therebetween, and means to cause vibration of the frame and member.

3. A vibrating unit comprising a channel, for a fluid, formed to direct the fluid in a definite path, a resilient supporting element disposed in the channel, an apertured member disposed across the path of the fluid, a frame carrying the apertured member and supported by the resilient element, flexible strips disposed between the frame and the member adjacent the latter to form a fluid seal therebetween, and means to cause vibration of the frame and member.

4. A vibrating unit comprising a channel, for a fluid, formed to direct the fluid in a definite path, a screen member disposed across the path of fluid, a frame carrying the screen member disposed in the channel, a vibrating element, means including cushioning members connecting the vibrating element to the frame, and means to cause actuation of the vibrating element to vibrate the frame and screen member.

5. A vibrating unit comprising a channel, for a fluid, formed to direct the fluid in a definite path, a screen member disposed across the path of fluid, a frame carrying the screen member, a vibrating element, means including spaced cushioning members surrounding the vibrating element to connect the vibrating element to the frame, and means to cause actuation of the vibrating element to cause vibration of the frame and screen member through the cushioning members.

6. A vibrating unit comprising a channel, for a fluid, formed to direct the fluid in a definite path, a screen element disposed across the said path, a resilient member disposed in the channel and formed to completely support the screen element and to close the channel against the passage of the fluid therethrough other than through the element, and means to vibrate the element.

7. A vibrating unit comprising a channel, for a fluid, formed to direct the fluid in a definite path, a vibrating frame disposed in the channel, a screen carried by the frame, means disposed between the screen and the frame to form a fluid seal therebetween, a resilient support for the frame disposed in the channel and serving as a fluid seal between the frame and the channel, a vibrating element, cushioning means to connect the element to the frame, and means to cause actuation of the element to vibrate the frame and screen.

8. A vibrating unit comprising a channel, for a fluid, formed to direct the fluid in a definite path, a frame disposed in the channel and having a fluid passageway therethrough, a screen mounted in the frame and covering the passageway therein, a resilient member supporting the frame and closing the path of fluid excepting through the screen, and means to cause vibration of the frame on the resilient member to vibrate the screen.

9. A vibrating unit comprising a channel, for a fluid, having a bottom and vertical side walls to direct the fluid in a definite path, a hollow frame disposed in the channel, a screen supported by

the frame, resilient supporting elements disposed between the frame and the bottom and side walls of the channel to support the frame and screen for vibratory movement across the said path, and means to vibrate the frame and screen on the resilient elements.

10. A vibrating unit comprising a channel, for a fluid, having a bottom and vertical side walls to direct the fluid in a definite path, a hollow frame disposed transversely of the path in the channel, a screen supported by the frame, resilient supporting elements disposed between the frame and the bottom and side walls of the channel to support the frame and screen for vibratory movement across the said path and to seal the channel against the passage of fluid therethrough other than through the screen, and means to vibrate the frame and screen on the resilient elements.

11. A vibrating unit comprising a channel, for a fluid, having a bottom and vertical side walls to direct the fluid in a definite path, companion grooved members disposed adjacent the bottom and side walls of the channel in a plane transverse the said path, a hollow frame disposed in the plane with the grooved members and having grooves therein, a screen supported by the frame, resilient supporting elements disposed in the grooves of the members and the frame to support the frame for vibratory movement, and means 30 to vibrate the frame and screen on the resilient elements.

12. A vibrating unit comprising a channel, for a fluid, having a bottom and vertical side walls to direct the fluid in a definite path, companion grooved members disposed adjacent the bottom and side walls of the channel in a plane transverse the said path, a hollow frame disposed in the plane with the grooved members and having grooves therein, a screen supported by the frame, resilient supporting elements disposed in the grooves of the members and the frame to support the frame for vibratory movement and to close the channel against the passage of the fluid therethrough other than through the screen, and means to vibrate the frame and screen on the resilient elements.

13. A vibrating unit comprising a channel, for a fluid, formed to direct the fluid in a definite path, an apertured member, a resilient element to support the member in the channel across the 20 path of the fluid and constantly serve as a dam against the passage of the fluid other than through the member, a cylindrical element, means including circular resilient cushions surrounding the element to resiliently connect the element to the frame, and means to cause vibration of the element and through the cushions cause vibration of the frame and apertured member.

FRANK EMERY HUTCHISON.
